ABSTRACT OF THE DISCLOSURE

A flat knitting method and apparatus for bringing about a change in the width of the knitted fabric particularly in connection with the knitting of a collar or neck region of a garment. The knitting machine includes a series of longitudinally displaceable needle assemblies movable in opposed directions between operative and inoperative positions, and preselected needle assemblies are displaced in one of these directions by a displacing means which may be automatically actuated, to bring about in this way a change in the width of the knitted fabric. Where the displacing means is used to displace selected needles to inoperative positions, the loops carried thereby are transferred to needles which continue to participate in the knitting, and the displacing means preferably takes the form of swingable butt-engaging members which turn about a predetermined axis to produce the displacement of selected needle assemblies.

BACKGROUND OF THE INVENTION

The present invention relates to knitting and in particular to flat knitting.

The present invention relates especially to that part of a knitting apparatus and method which brings about a change in the width of a knitted fabric. For example, during the knitting of the neck or collar regions of a garment it is necessary to gradually reduce the width of the knitted fabric.

Although there are known methods and apparatus for achieving these results, at the present time it is necessary to interrupt the operation of the machine in order to reduce or increase the number of needles which participate in the knitting operations.

Also, the known constructions are relatively complex and do not operate with the precision which is desired. Furthermore, with the known construction difficulties are encountered in incorporating the known constructions into existing knitting machines.

SUMMARY OF THE INVENTION

It is accordingly a primary objective of the current invention to provide a method and apparatus which will avoid the above drawbacks.

In particular, it is an objective of the invention to incorporate into the knitting machine needle-selecting elements which will operate precisely at the required instants for effecting an increase or decrease necessary to provide the desired shape to the collar or neck region of a garment.

In particular, it is an object of the invention to provide a needle-selecting mechanism of the above type enabling the neck regions of various articles of clothing to be manufactured with this type of machine without requiring any interruption in the operation thereof, so that in this way an increase in the efficiency of the machine operation is achieved.

Furthermore, it is an object of the invention to provide a construction wherein the actuation and movement of all the various components are brought about under conditions of complete safety with the needles and jack sinkers

2

being actuated so as to be put into or out of operation in an entirely automatic manner.

Also, it is an object of the invention to provide a structure of simple design and precise operation which can be incorporated into a knitting machine without any difficulty or complications.

According to the method and apparatus of the invention the decrease or increase in the needle assemblies participating in the knitting operations of the flat knitting machine, so as to provide for the production of clothing having decreasing width, for example, at the neck or collar regions, is brought about while transferring loops with respect to the needles which are displaced between their operative and inoperative positions. Thus, the longitudinally shiftable needle assemblies include butts engaged by butt-engaging members of the displacing means of the invention, so that through these butt-engaging members one or more needle assemblies can be shifted between operative and inoperative positions while transferring loops between needle assemblies so as to bring about the desired decrease or increase in the number of loops and thus provide for the garment a shape conforming to a portion thereof which changes in width such as the neck or collar region.

BRIEF DESCRIPTION OF DRAWINGS

The invention is illustrated by way of example in the accompanying drawings which form part of this application and in which:

30 FIG. 1 is a diagrammatic illustration of the primary components of a flat knitting machine carriage provided with the structure of the invention, FIG. 1 showing components situated to the right and to the left and in front of and behind the carriage;

35 FIGS. 2A-2F illustrate six consecutive positions of one set of components to illustrate the sequential operating which take place during selections of needles displaced with respect to other needles of this series; and

FIGS. 3A-3C are schematic longitudinal sections 40 through the needle bed illustrating three sequential positions of the components.

DESCRIPTION OF A PREFERRED EMBODIMENT

Referring now to FIG. 1, the mechanism illustrated therein includes cams 1 and 2 for raising needles at the rear portion of the carriage and cams 3 and 4 for raising needles at the forward portion of the carriage. The illustrated structure also includes cams 5 and 6 for raising the jack sinkers at the rear part of the carriage and cams 7 and 8 for raising the jack sinkers at the front part of the carriage.

The structure illustrated in FIG. 1 also includes, as shown at the central portion of FIG. 1, cams 9, 10, 11 and 12 which are the stitch- or loop-forming cams and which are arranged in pairs, as illustrated. These pairs of loop-forming cams are respectively arranged at the front of and to the rear of the conventional faces of the moving carriage of the knitting machine. These stitch or loop-forming cams are analogous to those provided in standard flat knitting machines.

60 The present invention resides primarily at the zones of A, B, C, and D of FIG. 1. The elements situated at zone A are perfectly symmetrical with respect to those situated at zone B, and in the same way the elements situated at zone C are symmetrical with those situated at zone D. The elements in these zones are of two types, namely cams and displacing means for displacing needle assemblies, this displacing means taking the form of butt-engaging members. The latter include a butt-engaging member 13 at zone A and its equivalent counterpart 13a at zone B. These members 13 and 13a have two basic positions, namely the shaded position representing the

inoperative position and the unshaded position representing the operative position. In addition, zones A and B include a butt-engaging member 14 with its symmetrical counterpart 14a at zone B, and it will be noted that there are also butt-engaging members 15 and 15a respectively situated symmetrically with respect to each other at zones A and B. Finally, there are butt-engaging components 16 and 16a also symmetrically situated with respect to each other at the zones A and B. All of these members are shown in the shaded illustration in their inoperative positions and in the unshaded illustration in their operative positions. The butt-engaging elements 13 and 13a perform a function different from that of the remaining butt-engaging members, as will be apparent from the description below.

The groups of symmetrically arranged cams of the zones A and B are shown at 17 and 17a, 18 and 18a, and 19 and 19a, respectively, with these pairs of cams carrying out separate and specific functions, as will be apparent from the description below.

The arrangement illustrated in FIG. 1 is completed by the components shown at the zones C and D, these components also being symmetrically arranged and including the butt-engaging members 20 and 20a, 21 and 21a and 22 and 22a, these latter members also being illustrated in a shaded manner at their inoperative locations and in an unshaded manner at their working locations. At these zones C and D there are also the symmetrically arranged cams 23 and 23a, 24 and 24a, and 25 and 25a, these cams being symmetrically arranged in pairs, as is apparent from FIG. 1.

FIGS. 2A-2F illustrate the sequence of operations which take place at the zone A, and it is to be understood that corresponding operations take place symmetrically at the zone B. With the operations illustrated in FIGS. 2A-2F, the first and eighth needle assemblies of the series of needle assemblies are displaced with the method and apparatus of the invention. It will be noted that a part of the cam 19 is illustrated as well as the butt-engaging members 15 and 16, which are shown in FIG. 2A in their operative location. A previously set pattern selecting mechanism of known construction brings about the automatic situation of the members 15 and 16 in the operative positions illustrated at the proper instant in a fully automatic manner. Thus, at FIG. 2A, there is illustrated the establishment of contact between the butt-engaging member 15 and the first needle and between the butt-engaging member 16 and the eighth needle, of a series of needle assemblies 26. In other words, these needle assemblies will in a conventional manner be provided with components having the butts illustrated in FIGS. 2A-2F situated to be engaged by the members 15 and 16 so that the assemblies can be shifted in a manner referred to below.

It will be noted that at the next position (FIG. 2B), the member 15 has raised the first needle of the series while the member 16 has raised the eighth needle of the series. Subsequently at the position shown in FIG. 2C the needle assemblies have been displaced further beyond the position shown in FIG. 2B. These operations take place while the butt-engaging members 15 and 16 swing along a circular path about an axis determined by the pivot means 27 schematically illustrated. Thus, the members 15 and 16 are only required to move along circular paths while displacing the needle assemblies axially.

Referring to the next illustration in FIG. 2D, it will be seen that during the continued turning of members 15 and 16, member 16 has moved beyond the eighth needle assembly while the member 15 continues to turn while still raising the first needle assembly.

The FIG. 2E illustrates the parts at an instant after their positions shown in FIG. 2D where during the continued movement of the members 15 and 16 about their common turning axis the first assembly has been raised still further and the eighth needle assembly is advancing

under its own momentum toward the cam 19, and at the final position shown in FIG. 2F, the members 15 and 16 have reached their inoperative positions and the first and eighth needle assemblies will continue under their own momentum until they reach the cam 19.

Referring now to FIGS. 3A-3C, the knitting bar 28 is shown therein in three sequential positions, respectively. At the position of FIG. 3A the needle butt 29 of the illustrated assembly and the butt 30 of the jack sinker 10 shown at their relative elevations with respect to the cam assemblies 3, 4 and 7, 8, respectively, the structure also including the spring member 31 which in position of FIG. 3A is inoperative with respect to the cams, 7, 8 and 3, 4. This latter position of the spring 31 is maintained as a 15 result of the rod 32 which in this position of the parts is situated within the notch 33 at the free end of the lower limb of spring 31, as viewed in FIGS. 3A-3C. The spring has an inclined portion 34 which engages the rod 32 when the spring 31 is in its operative position.

20 The structure includes the plurality of butt-engaging members 13 and 14, 15 and 16 forming the displacing means of the invention and their corresponding symmetrical counterparts at the zone B together with those at the other side of the carriage, these butt-engaging members 25 ascending in order to place the jack sinkers and needles of the needle assemblies into or out of operation. When the butt-engaging member 13, known as an "increasing" member, is in its unshaded, operative position, it engages the butts of the first two jack sinkers which are in their 30 inoperative positions and lifts them until the members 13 and 13a reach their shaded, inoperative positions, thus displacing the corresponding jack sinkers and needles of the needle assemblies into operative knitting positions, so that these members 13 and 13a of the displacing means of 35 the invention can bring about an increase in the width of the fabric by introducing more needles into the knitting operations.

40 In contrast, the butt-engaging members 14, 15 and 16 together with their symmetrical counterparts and those on the other side of the carriage, are "decreasing" members and always act in unison to displace needle assemblies from operative to inoperative positions where they will no longer participate in the knitting operations. The butt-engaging members 15 and 16, and their counterparts, will 45 respectively raise the first and eighth needle assemblies of the series 26 while these members 15 and 16 move from their unshaded, operative to their shaded, inoperative, positions, as described above in connection with FIGS. 50 2A-2F. As a result, the needle assemblies will follow the profile of the cams 19 or 19a, these cams acting as transfer cams so as to cause the loops or stitches to be transferred over to the needle assemblies on the opposite needle head where these loops or stitches are received. This result is 55 achieved because just prior thereto the cams 24 and 24a have been actuated so as to perform their specific function of opening the tongues or latches of the needles, and also the cams 23 and 23a have been actuated so as to perform their specific function of receiving the loops or 60 stitches, these cams being associated with the opposite side of the carriage.

Once the loop transfer has been carried out, the first and eighth needles of the series descend, and when the first needle assembly has a butt thereof impinging against the butt-engaging member 14 or 14a of the displacing means 65 of the invention, with these latter members in the unshaded positions, so that the members 14 or 14a have at this time been automatically situated beyond their shaded inoperative positions in the unshaded operative positions by the automatic mechanism referred to above.

70 At the zones C and D, it will be noted that there are no butt-engaging members 16 or 16a for acting on the eighth needle assemblies.

Referring now to FIGS. 3A-3C, the jack sinker of each needle assembly is shown after the butt 30 thereof has 75 been raised by the butt-engaging member 13 or 13a until

the butt 30 reaches the position shown in FIG. 3C. At this time the jack sinker continues to rise due to the action of the cams 7 and 8 on the butt 30 of the jack sinker, until the jack sinker reaches the position shown at FIG. 3B. In this position the jack sinker has acted upon the butt 29 of the needle of the needle assembly so as to displace the needle all the way out to the position shown at FIG. 3B. In this position the jack sinker has raised the needle to its casting off location, while the spring 31 remains in its operative working position with respect to the holding rod 32 thereof which releasably maintains the spring 31 in one of the other of its positions in the manner described above.

Thus, it will be seen that the above-described structure of the invention provides a simple and highly effective means for increasing or decreasing the width of a knitted garment, as at the neck or collar region thereof.

What is claimed is:

1. In a flat knitting machine, a series of needle assemblies displaceable in opposed directions between operative and inoperative locations, and displacing means co-acting with preselected needle assemblies of said series for displacing the selected needle assemblies in one of said directions to bring about a change in the width of the knitted fabric, said needle assemblies respectively including butts to be engaged by said displacing means, and said displacing means including swingable butt-engaging members to engage the butts of selected assemblies to displace the latter axially during swinging of said butt-engaging members, said butt-engaging members turning about a predetermined axis, and said displacing means turning a plurality of said butt-engaging members as a unit while

engaging a plurality of said assemblies, for simultaneously displacing the latter.

2. The combination of claim 1 and wherein said assemblies each include a needle and a jack sinker, and said displacing means operating automatically.

3. In a method of operating a flat knitting machine, having needle assemblies displaceable in opposed directions between operative and inoperative positions, the steps of displacing selected needle assemblies in one of said directions to bring about a change in the width of the knitted fabric, with said assemblies being displaced from operative to inoperative positions for reducing the width of the knitted fabric, and transferring loops carried by needle assemblies which are displaced to inoperative positions to other needle assemblies which continue to participate in the knitting so as to be combined with the loops on said other needle assemblies.

4. In a method as recited in claim 3 and wherein the decrease in the width of the knitted fabric is carried out in connection with the knitting of a collar or neck region of a garment.
